Attorney

UNITED STATES PATENT OFFICE.

ALBERT B. HEINKE, OF ATLANTA, GEORGIA.

STOCKING.

1,399,299.

Specification of Letters Patent.

Patented Dec. 6, 1921.

Application filed May 17, 1921. Serial No. 470,363.

To all whom it may concern:

Be it known that I, ALBERT B. HEINKE, a citizen of the United States, residing at Atlanta, in the county of Fulton and State 5 of Georgia, have invented certain new and useful Improvements in Stockings, of which the following is a specification.

My invention relates to the method of knitting stockings having a seamless leg 10 and heel and a full fashioned foot. The object of my invention is to form a stocking having a leg and heel formed in a continuous operation and shaped in the manner in which stockings are knitted upon a circular 15 machine for knitting seamless stockings; terminating the leg, at the instep, and the heel with a loose course formed in the fabric, slitting the heel along the bottom and back center line to permit the fabric to be 20 extended, with the edges of the heel and instep placed in a straight line, and transferring the same to a machine for forming a full fashioned foot; knitting the foot to the instep and to the heel along the lines of the 25 said loose courses; folding the foot over upon itself and looping the toe together and seaming the foot from toe to heel along the edges of the foot, and extending the seaming along the slit portions of the heel 30 to join the same together and complete the stocking.

Referring to the accompanying drawing, Figure 1, is a side elevation of a stocking embodying my invention; Fig. 2 is a side 35 elevation of a leg and heel of a stocking showing the first step in the operation of my improved method; Fig. 3 is a view showing the back or edge of Fig. 2, and Fig. 4, is a view in elevation of the stocking, showing the heel split and a foot formed upon the heel.

In the drawings in which like reference characters refer to like parts 1 represents the stocking consisting of a leg 2 and a heel 45 3, which are formed in a continuous operation upon a circular machine, and known as a seamless stocking. The leg 2 terminates at the instep 4, as shown in Fig. 2. The heel 3 is completed and is properly shaped. 50 The shading upon the heel is to indicate that the rows of stitching or threads are continuous around the heel, and the line 5 indicates a gore formed in the heel by the machine in finishing the spherical shaped heel.

The fabric is terminated with a loose

course of stitching, extending along the line 7 of the instep 4 and the line 8 of the heel 3. The loose course facilitates in transferring fabric from a circular machine to a 60 straight machine.

The leg and heel are made with a drop stitch forming a line 9 throughout the vertical back center line thereof. The line 9 thus formed in the heel is utilized as a guide 65 in carrying out my method.

The heel is slit along said line 9, forming slit portions or edges 12 and 13 of the heel. The slitting of the heel extends to a point 14, along the guide line 9 of the heel, which 70 permits the fabric to be placed in a straight line, as indicated by the line 15—15 Fig. 4, and transferred to a straight machine for forming the foot 20; which is knitted in flat formation and joined to the leg along 75 the line 7 of the instep, and to the heel along the lines 8, thus forming a full fashioned foot.

The stocking is now looped together at the toe in the usual manner, the edges 21 80 and 22 of the foot 20 are seamed together and the seaming is continued around the heel for joining the portions 12 and 13 of the heel together, restoring the heel to its original formation and completing the 85 stocking.

Heretofore stockings have been made by different methods, one of which forms a seamless stocking made upon a circular knitting machine which forms the leg with 90 the heel formed thereon; also the foot and the toe. There is another method forming what is known as a full fashioned stocking, made on a flat machine as distinguished from a circular machine. By the latter 95 method, the leg and heel are made in a flat or open form, then transferred to a flat footing machine which forms the foot and the toe. The latter are then looped and the sole of the foot and the entire back of the 100 leg is seamed to complete the stocking.

My present method, as above described, has the advantage over the previously known methods by forming a leg and heel on a circular machine, and forming the foot 105 and toe on a flat full fashioned knitting machine. By this method a stocking is produced having a properly shaped and round seamless heel, and having a full fashioned foot and toe, thus saving in the cost of manufacture, increasing the production and combining the best features of the seamless and

full fashioned stockings. And my method eliminates the formation of the heel separately from the leg, also any looping of the heel, as is now necessary in all other methods for making a full fashioned stocking.

Having thus described my invention, I claim and desire to secure by Letters Patent:

1. The method of forming a stocking by knitting a seamless leg and heel, slitting the heel to permit the fabric to be extended in flat formation, and knitting a foot in flat formation to the heel and end of the leg and seaming together the edges of the foot and the edges of the heel to complete the stocking.

2. The method of forming a stocking by knitting a seamless leg and heel in one continuous operation, slitting the heel to permit the fabric to be extended in flat formation, and knitting a foot in flat formation to the heel and to the end of the leg and seaming together the edges of the foot and the edges of the heel to complete the stocking.

3. The method of forming a stocking by knitting a seamless leg terminating at the instep on one-half of the leg, and continuing to knit the heel upon the other half of the leg forming a seamless heel, and forming a loose course around the termination of the heel and instep, slitting the fabric to per-

mit the same to be extended in flat formation, and knitting a foot in flat formation to the heel and to the instep, and seaming together the edges of the foot and the slit edges of the fabric to complete the stocking.

4. The method of forming a stocking by knitting the leg in circular form with a heel formed as a continuation upon the leg, terminating the leg and heel with a loose course of stitching, slitting the heel along the center line of the bottom and the back to permit the fabric to be straightened out and knitting a full fashioned foot in flat formation upon the end of the leg and heel and seaming together the outside edges of the foot, and heel, forming the sole of the foot and bottom and back of heel.

5. The method of forming a stocking by knitting a seamless leg, and heel with a drop stitch extending along the center line of the bottom and back of the heel by slitting the heel along the line of the drop stitch to permit the fabric to be extended in flat formation, and knitting a foot in flat formation to the heel and leg, and seaming together the edges of the foot and the slit edges of the heel to complete the stocking.

In testimony whereof I affix my signature.

ALBERT B. HEINKE.
